UNITED STATES PATENT OFFICE

ROBERT J. MEISTER, OF CINCINNATI, OHIO

SOAP SAVER

Application filed May 9, 1930. Serial No. 451,154.

This invention relates to a utensil for use in dish washing, and is of a special utility in the larger eating places, hotels, restaurants, and the like where glassware and certain items of china ware are not trusted to machines, but are washed by hand.

An object of the invention is to provide a device whereby soap substances in the nature of powders, flakes, chips and the like may be liberated in the form of soap solutions as needed in the dish water.

Another object is to provide a device that will not liberate excessive or wasteful quantities of its contents even though it is left in the dish washing tub or receptacle.

Another object is to provide a device wherein the soap materials used may undergo the expected changes without loss or wastage and yet deliver the necessary amount of soap in solution to the dish water.

Another object is to provide a device of this type which is of ample capacity and of such shape as to be easily grasped and which provides against rolling about in the vessel and yet eliminates largely the danger of breakage of glassware and the like.

These and other objects are attained by the means described herein and disclosed in the accompanying drawing in which:

Fig. 1 is a perspective view of a soap saving container of the invention.

Fig. 2 is a view taken on line 2—2 and showing an auxiliary member in position.

The device comprises a container body 10 which is preferably made of non-corrodible sheet metal such as Monel metal or, if desired a baster sheet metal with or without a protective coating of nickel or chromium plate so that it will withstand the effects of soap and water. This container has ends 11 and 12, the former of which has a filling opening 13 in which is securely mounted a threaded collar 14 which receives a screw threaded closure plug 15. The ends 11 and 12 are each provided at a common end with

a perforation 16 and 17 respectively, these perforations being closely adjacent one of the short curves 18 of the body 10. The body is preferably of a generally elliptical cross section. The perforations 16 and 17 are thus aligned at opposite ends of a relatively narrow groove formed on the inside by the contour of the body 10. This facilitates the use of a conditioning implement 19 which may be a simple length of thin wire provided if desired with a finger loop 20. It is desirable to have the cap 15 fit very tightly so that when the device is filled with soap chips, flakes, or powder, and is placed in the bottom of a dish washing pan or vessel only a very limited circulation of water may take place.

The operation of the device is as follows. The container may be filled completely with soap in the form of powder, chips, flakes or the like and thrown into the bottom of the dish washing vessel. When the dish washer requires soapy water he merely shakes the container in the water so that some of the water which has entered the container and dissolved part of the soap therein may discharge small quantities of soap solution into the body of dish water. The dish washer does not remove the device from the vessel but proceeds to wash the dishes in the sufficiently soapy water and may then drain the vessel without taking the trouble to remove the soap saver container of the invention. It is to be understood that flakes, powder, and chips of the sort usually purchased for these uses will take the form of a jell after continued contact with water, and that this congealation will sometimes cause a stoppage of the two small perforations 16 and 17. In such event the cleaning implement or wire 19 which may be suspended handily to the dish washing vessel is quickly thrust into one of the perforations and, using the curvature of the body 10 as a guide is readily pushed through the container and out of the opposite perforation. This again allows the

limited circulation of water into and from the container but no solid particles or masses of soap will find their way through the small perforations.

It is to be understood that this soap saver is not to be confused with the wire cage type of soap holding devices since these usually have only so much body structure as to prevent floating away of the soap. The soap goes into solution entirely too readily in order to effect any substantial saving and these are intended to be inserted in the water and shaken only until the water is sufficiently soapy for its intended purpose. The present device on the contrary not only permits of the use of all forms of soap, but precludes waste of such soap even by the most careless of employees. The device of the present invention has been used with an effective saving of 30 to 40% of the usual amount of soap materials in any given time. At the same time it eliminates the heretofore frequent stoppage of waste-pipes because it totally eliminates the dumping into the drain of partly dissolved soap chips and flakes, or the like.

The present invention is not to be understood as limited to the exact detail of construction since the shape of the body and the particular form of watertight filling cap may readily be altered.

What is claimed is:

1. As a new article of manufacture a soap saver comprising an elongated non-corrodible container having a restricted perforation in each of its opposite ends and a closable filling opening disposed in one end of the container.
2. As a new article of manufacture a soap saver comprising an elongated container substantially elliptical in cross section and having a single restricted perforation in each of its opposite ends said perforations being aligned and disposed in its respective end closely adjacent the side wall of the container.
3. As a new article of manufacture a soap saver comprising an elongated receptacle of non-corrodible material, substantially elliptical in cross section and having a restricted perforation in each of its opposite ends, and closable means whereby soap materials such as powders, chips, flakes and the like may be inserted, the perforations being aligned and closely adjacent the side wall to provide for the guiding of a conditioning implement for said perforations.
4. In a soap saver the combination of a container body of such cross section as to permit only limited rolling thereof, said container having at one end a closable filling opening, the container further having two remotely spaced restricted perforations to permit entry and exit of water whereby soap in the container may leave the container in solution form only, and in limited quantities.
5. In a soap saver for hand dishwashing the combination of an elongated metallic con-

tainer having a generally flattened cross-section whereby the inner face of the side wall thereof provides a guideway, the opposite ends of said container each being provided with a single restricted perforation immediately adjacent said guideway and a removable filling cap for the container and spaced from said restricted perforation.

In testimony whereof, I have hereunto subscribed my name this 5th day of May, 1930.

ROBERT J. MEISTER.
